(57) **CLAIM**

The ornamental design for a refrigerated counter, as shown and described.

DESCRIPTION

Reproduction 1.1 is a front perspective view of a refrigerated counter showing my new design;

Reproduction 1.2 is a front view thereof;

Reproduction 1.3 is a right side view thereof;

Reproduction 1.4 is a left side view thereof;

Reproduction 1.5 is a rear view thereof;

Reproduction 1.6 is a top view thereof;

Reproduction 1.7 is a rear perspective view thereof.

Reproduction 2.1 is a front perspective view of a second embodiment of a refrigerated counter showing my new design;

Reproduction 2.2 is a front view thereof;

Reproduction 2.3 is a right side view thereof;

Reproduction 2.4 is a left side perspective view thereof;

Reproduction 2.5 is a rear view thereof;

Reproduction 2.6 is a top view thereof; and;

Reproduction 2.7 is a rear perspective view thereof.

The features presented in broken lines illustrate portions of the refrigerated counter that form no part of the claimed design.
